UNITED STATES PATENT OFFICE.

CHESTER D. AINSWORTH, OF WOLLASTON, MASSACHUSETTS, ASSIGNOR, BY MESNE ASSIGNMENTS, TO CONDIT ELECTRICAL MANUFACTURING CORPORATION, OF BOSTON, MASSACHUSETTS, A CORPORATION OF MASSACHUSETTS.

CIRCUIT INTERRUPTER.

Application filed December 14, 1921. Serial No. 522,227.

To all whom it may concern:

Be it known that I, CHESTER D. AINSWORTH, a citizen of the United States, residing at Wollaston, in the county of Norfolk and State of Massachusetts, have invented an Improvement in Circuit Interrupters, of which the following is a specification.

This invention relates to electric switches and has particular reference to electrically-operated oil switches adapted to be enclosed removably in cells.

An object of this invention is generally to improve the construction and operation of an electric switch of the type above set forth.

A further object is to improve the operating mechanism of the switch.

Certain features of this invention are claimed in my co-pending applications, Serial No. 535,220, filed February 9, 1922; Serial No. 585,672, filed September 1, 1922; and Serial No. 522,228, filed December 14, 1921.

Fig. 1 is a side elevation of an electric switch embodying the invention contained in an enclosing cell which is illustrated diagrammatically.

Fig. 2 is a plan view of the switch with the electrically-controlled operating mechanism removed.

Fig. 3 is a longitudinal sectional elevation along line 3—3 of Fig. 2.

Fig. 4 is a front view of the switch of Fig. 2 with the oil receptacle partly broken away to illustrate the auxiliary contact members.

Fig. 5 is a plan section along line 5—5 of Fig. 3 and illustrates more particularly the switch operating mechanism.

Fig. 6 is a sectional detail illustrating the position of the operating mechanism in the open condition of the switch.

Fig. 7 is an end view of the auxiliary contact members.

Fig. 8 is a plan view of the movable switch member with the switch rod removed.

Fig. 9 is a detail illustrating the manner of guiding the upper end of the movable switch member for vertical movement.

As here shown the switch embodying my invention includes the oil receptacle 10 and the switch frame 11 which comprises a cover for said receptacle and is removably secured

to the top thereof by the bolts 12. Said switch is adapted to be contained in the cell 55 A and be supported in position therein on the track 13. For this purpose the oil receptacle is secured to and supported upon the platform 14. Said platform is provided with grooved wheels 15 adapted to engage 60 said track 13. The switch may be locked removably in position in the cell by the bolt 16 carried by said platform 14 and which is adapted to be threaded in an aperture in a bracket 17 secured to the track 13. 65

The switch is adapted normally to be operated by electrically-controlled means and, while said operating means may be disposed in any convenient relation with the switch, I prefer to mount said operating means on the switch and as a component part of the switch unit. 70

For this purpose, the switch frame 11 is formed with the substantially vertically disposed end flange 18 to which the electrically-controlled operating mechanism 19 is adapted to be secured rigidly and removably. 75 For certain purposes, I may secure said mechanism directly to said flange and for other purposes, I may interpose the adapter block 20 between said switch frame and mechanism. 80

The electrically-controlled operating mechanism 19 is adapted to be disposed externally of the cell while the switch is 85 adapted to be contained entirely within the cell. A plate 21 is carried by said adapter block 20 and is adapted to engage the opposite cell walls and form a part of the door of the cell. An upper door 22 may rest 90 removably upon said plate and a lower door 23 may hang removably from said plate to enclose the lower portion of the cell.

Said switch frame 11 is a dome-shaped casting and is adapted to enclose and support the switch-operating mechanism. The lower edge is formed with a groove 25 in which the upper edge of the oil receptacle is received. 95

Stationary switch members 26, which include the insulators 27 and conducting rods 28, are carried by said frame and are secured thereto by the clamps 26^a and depend into the oil receptacle. The lower ends of said switch members are passed through 100 apertures in and are secured to the insulat- 105

ing supporting bar 29 by the clamps 29^a; and said bar is secured to the switch frame by the brackets 30.

The movable switch member 31 includes 5 the insulating rod 32 bearing the inverted brush-member 33 and auxiliary contact members hereinafter to be more fully described at its lower end and has the threaded rod 34 secured in its upper end.

10 The switch herein illustrated is of the upbreak type and the movable switch-member is moved upwardly to interrupt the circuit through the switch and downwardly to close the circuit.

15 The insulating rod 32 of said movable switch member is passed through an aperture in said supporting bar 29 and the upper end of said switch member is guided for vertical movement in a straight line.

20 The guiding means include the two brackets 35 secured to said supporting bar 29 on opposite sides of the movable switch member; and said brackets are formed with the vertical slots 36 therein. A block 37 is 25 adjustably threaded on the rod 34 of said movable switch member and is held in position thereon by the nut 38. Pins, here shown as shoulder screws 39, are passed through the slots 36 in said brackets 35 and 30 are fixed in the opposite sides of said block. Said pins are adapted to fit freely within said slots but without substantial lateral play therein and serve to constrain the upper end of said movable switch member to move in 35 a line parallel to the slots.

An operating lever is arranged to move said movable switch member between switch-open and closed positions. Said lever comprises the two spaced arms 50 and the integral rear connecting portion 51. Said rear portion is formed with an aperture therethrough through which a pivot pin 52 is 40 passed; and the ends of said pin are extended through and journaled in apertures 45 in opposite walls of the switch frame. Said arms are extended on opposite sides of one of said stationary switch members and the outer ends of said arms are disposed on opposite sides of the block 37 carried by 50 the movable switch members. The outer ends of said arms are formed with the slots 54 and the pins 39 carried by said block 37 are extended through said slots. It is 55 obvious that as said arms are moved about its pivot the movable switch member will be carried with them.

An operating shaft 55 is journaled in suitable bearings in opposite side walls of the switch frame above said arms 50 and 60 extends beyond said side walls on both sides thereof. Arms 56 are fixed to said shaft within the switch frame and links 57 are pivotally connected by the pins 58 to the ends of said arms and by the pins 59 to 65 intermediate portions of said arms 50. Said

arms 56 and links 57 constitute toggle members by which the movable switch member is operated; and said toggle members are adapted to be moved nearly to an on-center position, as illustrated in Fig. 3, in the closed 70 condition of the switch.

A bumper 60 is adjustably secured, by means of the threaded rod 61 and check nut 62 to said arms 50 and is adapted to engage said operating shaft 55 when the movable switch member and operating mechanism is moved into switch-open position and absorb the energy of movement and also define the switch-open position of the movable switch member. 75

80 Downwardly depending arms 65 are fixed to each of the external ends of said operating shaft 55 and are adapted to be connected with a link connected with the electrically-controlled switch operating mechanism 19 and also with springs by which the movable switch member is moved into open position. Said arms may also serve to keep the operating shaft against axial displacement in the switch frame. 85

90 Dual means including springs are provided, each of which is arranged to function independently of the other to move the movable switch member to switch-open position. Said means include the rods 66 pivotally connected by said pins 67 to said arms 65 intermediate the ends thereof. The free ends of said rods are slidably received in and supported by the brackets 68 carried by the switch frame. Coil-springs 69 are disposed over said rods 66 between said brackets 68 and arms 65; and the outer ends of said springs bear against said brackets. Check nuts 70 are adjustably threaded on the inner ends of said rods adjacent said 95 arms 65, and the other ends of said springs bear against said nuts. 100

105 It will be apparent that said springs tend constantly to move and retain the movable switch member yieldingly in switch-open position and will be compressed by the action of the electrically-controlled operating mechanism in moving the movable switch member into switch closed position. The arrangement of dual springs disposed at the 110 opposite ends of the operating shaft 55 is advantageous in that the turning movement of one spring is counterbalanced by the other spring. Each spring alone is adapted 115 to counterbalance the weight of the operating mechanism and movable switch member and cause the opening of the switch and two springs provide increased assurance of reliability of operation. The disposition of the 120 springs on the outside of the switch casing is advantageous in that the springs may be under constant observation and failure of the switch to operate due to spring breakage may be guarded against. 125

130 Said arms 65 are extended beyond the

pivotal connections of the spring rods 66 therewith and are provided with apertures 71 by which said arms are adapted for connection with the electrically-controlled operating mechanism 19. Ordinarily but one of said arms 65 will be connected with the operating mechanism but said mechanism is so arranged that it may be operatively connected with either one or both of said arms.

10 As here shown, a link 72 is pivotally secured to a pin 73 extended through an aperture 71 in one of said arms and is pivotally secured to a rocker-arm 74 of said operating mechanism 19. It will be obvious that, 15 as said arm is rocked in its bearings, said switch will be opened and closed.

The top wall of said switch frame is formed with an aperture disposed above and vertically in line with the movable switch member and through which the brush tension of said member may be adjusted; and said aperture is normally closed by the removable plate 75.

25 The arrangement of the stationary and movable auxiliary contact members herein illustrated is of importance; and the arrangement is such that the movable contact members tend to be drawn into more secure engagement with the stationary contact members when the switch is carrying relatively high values of current, instead of the usual tendency of the common form of contact members to separate under heavy loads.

35 The brush member 33 is secured to the member 80 having the upwardly extended ears 81. The switch rod 32 is disposed between and secured pivotally to said ears by the pin 82. Said member 80 is adapted to 40 carry a frame which supports the auxiliary contact members. Said frame includes the two bars 84 which are secured to the ears 81 of said member 80 and are reflexed outwardly to provide the end portions 84^a which are extended laterally beyond the brush member. Flexible members 85 are secured to the ends of said bars 84 by the bolts 86 and extended downwardly beyond the brush member; and auxiliary contact 45 members 87 are secured removably to the lower ends of said members. Side tie-members 88 are secured to the flexible members on the same side of the brush member, also by said bolts 86; and end tie members serve 50 to connect the ends of said bars 84, whereby rigidly to support the auxiliary contact members in position.

The stationary auxiliary contact members are carried by the members 90 which are secured to the under side of the main contact blocks 91 of the stationary switch members. Said members are formed with the downwardly and outwardly reflexed end portions 90^a. The auxiliary contact members comprise the plates 92, which may be

somewhat flexible, if desired, and said plates are secured by the bolts 93 to said reflexed end-portions 90^a of said members 90. Said plates 92 extend upwardly and inwardly above the main contact blocks 91; and the upper end-portions 92^a are reflexed inwardly as illustrated in Fig. 7.

When the movable switch member is being moved into switch closed position the auxiliary movable contact members 87 engage the upper portions of said contact plates, before the brush member engages the contact blocks 91, and slides in engagement with said plates, and the flexible members 85 are flexed outwardly while maintaining the engagement of the auxiliary contact members, as illustrated in Fig. 4.

With this arrangement of auxiliary contact members, the magnetic effect of a high value of current in the circuit controlled by the switch is to tend to press the contact members into a more firm engagement than that resulting from the spring pressure of said resilient members 85 alone.

A long wiping engagement of the contact members is obtained and the movable switch member attains a considerable speed of opening after the main current-carrying members have separated and before the auxiliary contact members have separated so that, when said auxiliary contact members are finally separated, the arc may be rapidly extinguished and the circuit-interrupting capacity of the switch is thereby enhanced.

The invention may be contained in other modifications without departing from the spirit thereof.

I claim:

1. An electric switch including a casing comprising an oil receptacle and a switch frame comprising a cover for the oil receptacle, movable and stationary switch members and operating mechanism disposed within the casing and supported by said switch frame, said operating mechanism including an operating shaft pivotally supported by said switch frame and extended therethrough, electrically-operated switch-operating mechanism supported externally on said switch frame, and an operating member connecting said electrically operated mechanism and the extended end of said shaft.

2. An electric switch including a casing comprising an oil receptacle and a switch frame comprising a cover for the oil receptacle, movable and stationary switch members and operating mechanism disposed within the casing and supported by said switch frame, said operating mechanism including an operating shaft pivotally supported by said switch frame and extended therethrough, electrically-operated switch-operating mechanism supported externally

- on said switch frame, an arm fixed to an extended end of said shaft, and means including a connecting rod connecting said electrically-operated mechanism and said arm.
5. An electric switch including a casing having aligned apertures formed in the opposite side walls thereof, stationary and movable switch members disposed within the casing, operating mechanism disposed within said casing including an operating shaft journalled in the apertures in said casing and extended externally beyond the side walls thereof in both directions, arms fixed to the extended ends of said shaft externally of the casing, electrically-operated switch-operating mechanism supported externally on said casing, means including a connecting rod connecting said electrically-operated mechanism with one of said arms, and a spring connecting said other arm and said casing.
4. An up-break electric switch including a casing, stationary and movable switch members disposed within the casing, operating mechanism disposed within said casing and arranged to move the movable switch member upward to open the switch and having a member extended externally of the casing, and a switch opening spring carried externally by the casing and connected with said extended member to bias the movable switch member for upward movement.
5. An up-break electric switch including a casing, stationary and movable switch members disposed within the casing, operating mechanism disposed within said casing and arranged to move the movable switch member upward to open the switch and having a member extended externally of the casing, and a switch-opening spring horizontally disposed externally of the casing and carried thereby and having means connecting it loosely with said extended member to bias the movable switch member for upward movement.
6. An up-break electric switch including a casing, stationary and movable switch members disposed within the casing, operating mechanism disposed within said casing and arranged to move the movable switch member upward to open the switch and having a member extended externally of the casing, and dual switch opening springs carried externally by the casing and having independent connections with said extended member, each of said springs arranged to act independently to open the switch.
7. An up-break electric switch including a casing, stationary and movable switch members disposed within the casing, operating mechanism disposed within said casing and arranged to move the movable switch member upward to open the switch and having a member extended externally of the casing on opposite sides thereof, and two switch-opening springs supported externally of the casing on opposite sides thereof, and means independently connecting said springs with said extended member.
8. An up-break electric switch including a casing, stationary and movable switch members and operating mechanism disposed within the casing, said operating mechanism arranged to move the movable switch member upward to open the switch and having a member extended externally of the casing and a mechanism counterbalancing compression spring supported externally by the casing and operatively connected with said extended member.
9. An electric switch including stationary and movable switch members, operating mechanism, a casing enclosing the aforesaid elements, and dual devices including springs associated with said mechanism and supported externally of said casing and each independently arranged to bias said mechanism for switch-opening movement.
10. An up-break electric switch including a casing, stationary and movable switch members and operating mechanism disposed within the casing, said operating mechanism arranged to move said movable switch member upward to open the switch and including an operating shaft extended horizontally through a wall of the casing, an arm fixed to said shaft externally of the casing, and a switch-opening compression spring carried externally by said casing and having an operating connection with said arm.
11. An electric switch including a casing, stationary and movable switch members and operating mechanism disposed within the casing, said operating mechanism having an operating member extended through a side wall externally of the casing, and switch-opening means carried externally by said casing including a rod having one end pivotally connected with said operating member and its other end slidably supported, and a spring encircling said rod having one end thereof in engagement with said rod and its other end in engagement with said casing.
12. An electric switch including a casing, stationary and movable switch members and operating mechanism disposed within the casing, said operating mechanism having an operating shaft extended through apertures in opposite side walls of the casing, arms fixed to the ends of said shaft externally on opposite sides of the casing, and dual switch-opening means carried externally by the casing, each switch-operating means including a rod pivotally connected with one of said arms, a bracket fixed to said casing in which the other end of said rod is slidably supported, and a spring encircling said rod and bearing against said rod and said bracket.
13. An electrically-operated electric switch

including an oil receptacle, a switch frame, comprising a cover for said oil receptacle, stationary and movable switch members carried by said frame and depending into 5 said oil receptacle, switch-operating mechanism carried by and disposed within said frame, and an operating coil including an armature disposed externally on and carried by said frame, and means connecting said 10 armature with said enclosed operating mechanism.

14. An electrically-operated electric switch comprising the combination of a closed receptacle, stationary and movable switch members enclosed therein, and an operating 15 coil carried externally by said receptacle having an armature, and means operably connecting said armature and movable switch member.

In testimony whereof, I have signed my 20 name to this specification.

CHESTER D. AINSWORTH.
